UNITED STATES PATENT OFFICE.

HARRY L. GRANT, OF TAMAQUA, PENNSYLVANIA, ASSIGNOR TO ATLAS POWDER COMPANY, OF WILMINGTON, DELAWARE, A CORPORATION OF DELAWARE.

PROTECTING DEVICE FOR ELECTRIC DETONATORS.

Application filed November 20, 1925. Serial No. 70,371.

This invention relates to a protecting device for electric detonators of the character of that shown in my copending application, Serial No. 748,214, filed on November 6, 5 1924.

Like the device of the application referred to, the protecting device of the present invention is intended to be applied to the lead-in wires of electric detonators and 10 to serve, while in position, to establish a short circuit between the two lead-in wires, so that any stray currents imposed upon the lead-in wires, outwardly of the point of application of said device, may not find 15 their way to the detonator and prematurely explode the same.

I am aware of the fact that it has been proposed to short circuit the main firing cable leading from the blasting machine. 20 However, that method is of utility only at the time of use. An important object of the present invention is to provide a structure which will be operative with respect to the individual detonators and their individual lead wires, at all times between the 25 time of manufacture of the detonator and until the same is actually exploded on the job, the structure being of particular utility during the time that the detonator is being 30 transported and while it is being handled about the work preliminary to the actual connection of its lead wires to the main firing cable. By individual lead wires I mean the lead wires forming part of and shipped 35 with the individual detonators and by which said detonators are connected to the main firing cable.

The present application is directed to the protection of a specific form of short circuiting shunt and method of applying the same to the lead-in wires of the individual blasting caps, at a point close enough to the termination of the insulation to practically prevent the creation of a difference of potential between the lead wires, inwardly of 40 the point of application of the shunt, under the influence of accidental or stray currents. In the provision of a structure of this character, which is used only once and then 45 thrown away, it is of importance that it be of a simple and inexpensive nature and one adapted to be applied rapidly by automatic machinery. With this end in view, I have 50 devised the shunt shown in the accompanying drawing wherein:

Fig. 1 is a perspective view of a clip or shunt constructed in accordance with the invention.

Fig. 2 is a side elevation of the detonator with the clip of Fig. 1 applied thereto, and 60

Fig. 3 is an end elevation of the shunt with the bared portions of the lead wires of the detonator in section.

Like numerals designate corresponding parts in all of the figures of the drawing. 65

Referring to the drawing, 5 designates the conventional electric detonator and 6 and 7 designate the usual lead-in wires of said detonator.

In the ordinary use of the detonator the 70 flow of current of sufficient strength past an igniting element 8, which connects the inner ends of the wires 6 and 7, explodes the detonator. The lead-in wires are insulated, as indicated at 9 and 10, for some 75 distance from the detonator and the ends of the lead-in wires are left bare beyond the point where the insulation terminates, to adapt them for ready application to the firing cable, leading from a blasting machine. 80

The shunt of the present invention is what may be termed a "snap-on" shunt. It comprises a resilient metallic structure consisting of a plate, bent upon itself, and provided with a longitudinally extending rib and 85 groove, in which groove the bared portions of the lead wires are held by the resilient action of the structure, which is preferably, though not necessarily, made of phosphor bronze. However, it is to be understood that 90 it may be made of any suitable conductive and resilient material.

By referring to Fig. 1, it will be seen that the shunt consists of a piece of metal bent upon itself to constitute the plate-like 95 portions 11 and 12. The portion 12 is provided with an outturned edge 13 to facilitate the entry of the lead wires, 6 and 7, between the webs or plates 11 and 12. The inner face of the plate 12 is grooved, as indicated 100 at 14, to provide a recess which extends throughout the length of the shunt and into which the wires 6 and 7 snap, and in which they are firmly held in engagement with each other, it being understood that the shunt, as a whole, is preferably positioned upon these lead wires with its inner end abutting snugly against the outer ends of the insulation of said lead wires. It is not 105 understood that the device is of utility 110

- only when actually touching the termination of the insulation. It will give a very appreciable measure of protection even when spaced somewhat from the insulation because the influences which might bring about such difference in potential between the lead wires as to explode the detonator, are not those sought to be created by an intelligent human agency but only those which might accidentally occur. Stray currents of such low E. M. F. as to escape ordinary notice constitute a marked source of danger and are rendered absolutely harmless by this invention.
- When the shunt is to be removed, at the time of use of the detonator, it may be slipped laterally from the wires or it may be stripped longitudinally therefrom. If stripped longitudinally from the wires, such stripping action tends to clean and brighten the wires and put them in condition to form an efficient electrical union with the main firing cable of the blasting machine.
- It is to be understood that the invention is not limited to the precise construction set forth but that it includes within its purview whatever changes fairly come within either the terms or the spirit of the appended claims.
- Having described my invention, what I claim is:
1. A shunt of the character described formed of an integral piece of sheet metal,

bent upon itself, one of the bent portions being longitudinally ribbed and grooved at a point spaced from the point of bending, with the grooved portion disposed inwardly, said grooved portion being of such amplitude as to receive both of the lead wires of a detonator and hold them into contact making engagement throughout the length of the grooved portion.

2. A structure as recited in claim 1 wherein one of said portions is slightly shorter than the other, and is provided with an outwardly turned edge which lies in substantial parallelism with the grooved portion.

3. The combination with a detonator having the individual bifilar lead wires, said lead wires having a covering of insulating material thereon for a portion of their length, outwardly, and being bare therebeyond, of a shunt formed of an integral piece of sheet metal, bent upon itself, one of the bent portions being longitudinally ribbed and grooved with the grooved portion disposed inwardly, said grooved portion receiving both of the lead wires of the detonator and holding them in contact making engagement, at a point between the termination of the insulation and the outer ends of the said lead wires.

In testimony whereof he affixes his signature.

HARRY L. GRANT.
